UNITED STATES PATENT OFFICE

GILBERT W. GOODRIDGE, OF FAIRFIELD, CONNECTICUT, ASSIGNOR TO THE BRYANT ELECTRIC COMPANY, OF BRIDGEPORT, CONNECTICUT, A CORPORATION OF CONNECTICUT

ELECTRIC SWITCH

Application filed June 25, 1925. Serial No. 39,545.

My invention relates to electric switches, and particularly to rotary snap switches. The object of my invention is to provide an improved drive connection between the switch handle and the switch spindle.

In the accompanying drawings—

Fig. 1 is a broken side elevation of a rotary snap switch to which my invention is applied in one form;

10 Fig. 2 is an enlarged section on the line 2—2, Fig. 1;

Fig. 3 is a partial elevation of the spindle showing a driving dog and its retainer; and

15 Fig. 4 is a detached perspective of these parts prior to assembly on the spindle.

The particular construction of the switch and of the handle do not enter into my invention, and need not be described in detail. It suffices to point out that the switch illustrated 20 comprises the usual insulating base 15, upon which the switch mechanism is mounted and enclosed by the switch cover 16. The spindle rises through the cover 16 and is actuated by a handle 17 which, in the form shown, corresponds to that illustrated in the copending application of Carl E. Anderson, Ser. No. 739,891, filed September 25, 1924, which application has become Patent No. 1,657,337.

25 The driving engagement between the handle 30 and spindle is effected through a driving dog 18 which is secured against rotation on the spindle 19 and is received in an appropriate recess 20 in the handle 17 when the parts are assembled, for example by means of a screw ferrule 21 carried by the handle and engaging the threaded end 22 of the spindle.

35 The torsion strains exerted by the handle incident to the operation of the switch are transmitted to the spindle through the dog 18 and are consequently imposed primarily upon the latter. It is desirable to reinforce the dog against these strains, which tend to rupture it, and my invention not only accomplishes this desirable end, but also simplifies the attachment of the dog to the spindle.

40 As clearly illustrated in Fig. 4, the driving dog 18 is offset from its enlarged base 23, and the latter is slotted or bifurcated at 24 to engage the slabbed area 25 of the spindle to establish a drive connection with the latter.

In order to retain the dog in position on the spindle, I provide a retaining stirrup 26 adapted to embrace the spindle and dog, thus preventing lateral escape of the base 23 from the spindle. Preferably the stirrup is split at 55 27 to form legs 28 and 29. The closed end of the stirrup is shaped at 30 to snugly fit the slabbed area 25 of the spindle, while at its open end the legs are spaced apart at 31 substantially the width of the driving dog 18, so that when the hooked ends 32 and 33 of the legs are brought together beyond the outer face of the dog 18, the latter is snugly held between the legs 28 and 29, while the hooked ends 32 and 33 prevent the lateral escape of the base 24 from the spindle. The slabbed area 60 25 on the spindle 19 is of a width substantially corresponding to the combined thickness of the base 23 of the driving dog and the stirrup 26. Consequently, when the parts are adjusted upon the spindle they are held against longitudinal displacement thereon as well as against lateral escape therefrom by the shoulders afforded by the ends of the flattened portion 25.

75 Before assembly the legs 28 and 29 of the stirrup 26 are sufficiently spread to permit the stirrup to be passed laterally onto the spindle into such position that the hooked ends 32 and 33 may be closed together beyond the outer face of the dog 18. In this position the stirrup not only serves as a retainer for the base of the dog but also as a reinforcement of the dog 18 itself, so that it is better able to withstand without injury the torsion strains imposed upon it on actuation of the switch.

80 Various modifications will occur to those dealing with the problem which do not depart from what I claim as my invention. The construction has two aspects—first, as a retainer for the driving dog, and second, as a reinforcer therefor. It would, for example, be possible to use the stirrup only as a retainer, in which case it need not be split, but might be slipped down over the end of the spindle and dog, embracing both, and thus holding the dog upon the spindle. It would of course be possible to split the stirrup at its opposite end and close it upon the spindle instead of upon the dog. Various other modi- 85 90 95 100 105 110 115 120 125 130 135 140 145 150 155 160

fications will readily occur to those dealing with the construction.

I claim as my invention—

1. In a rotary switch, a spindle, a spindle, a driving dog at the side of the spindle and substantially parallel thereto having an offset bifurcated base adapted to effect a drive engagement with the spindle, and means engaging the dog and spindle to hold the said base of the dog in engagement with the spindle.
2. In a rotary switch, a flattened spindle, a driving dog substantially parallel to the spindle and having an offset base engaging the flat area of the spindle to cause the dog and spindle to turn together, a split stirrup embracing the dog and spindle and serving to maintain the engagement of the base of the dog with the spindle, and means on the spindle restraining the dog and the stirrup from movement along the spindle.
3. In a rotary switch, a flattened spindle, a driving dog substantially parallel to the spindle and having a base engaging the flat area of the spindle to rotate therewith, a split stirrup clamped upon said dog and flat area of the spindle to reinforce the dog and maintain the engagement of its base with the spindle, and means on the spindle restraining the dog and the stirrup from movement along the spindle.
4. In a rotary switch, a switch spindle having a flattened portion with shoulders at the ends thereof, a driving dog substantially parallel to the spindle and having a slotted portion providing a surface in driving engagement with said flattened portion to cause the dog and spindle to turn together, a split stirrup having a flat inner surface in engagement with said flattened portion to restrain said stirrup from rotation relative to said spindle and having a portion resting over a portion of said dog and restraining said dog from lateral movement away from said spindle, said shoulders restraining said dog and said stirrup from movement along said spindle.

In testimony whereof I have signed my name to this specification.

GILBERT W. GOODRIDGE.
